Original application February 20, 1941, Serial No. 379,850. Divided and this application December 30, 1942, Serial No. 470,602

3 Claims. (Cl. 282—21)

This invention relates to manifolding or continuous forming stationery of the type utilized in autographic registers which present the forms successively upon a writing platen and which are effective for feeding, aligning and delivering the forms.

More particularly, this invention is directed to improvements in manifolding stationery which comprises a plurality of superimposed forms; or, in other words, a manifolding pack with the sets of forms separated from each other by means of weakened transverse lines which permit separation.

The present application constitutes a division of co-pending application Serial No. 379,850 filed February 20, 1941, and entitled "Autographic register," which application has now issued into Patent No. 2,326,109 dated August 10, 1943. The register disclosed in the co-pending application is effective for feeding the continuous form stationery of this invention.

It has been an object of the present inventor to provide manifolding stationery which is formed so as to permit accurate and positive alignment of the forms during each feeding operation and which may be fed through the same register for this purpose regardless of variation in the lengths of the forms. The improvements particularly lie in the arrangement of the feeding apertures so as to permit feeding, aligning and dispensing in a register of the type disclosed in the co-pending application.

In the co-pending application, the inventor has provided an autographic register which utilizes cooperating sets of discs or rolls, upper and lower, to feed and align the improved forms by virtue of their feeding relationship to apertures in the forms. The rolls are manually operated by a crank which is fixed to one end of the shaft carrying the lower set of rolls. The upper rolls are in positive transmission connection with the lower rolls by gears, and are carried on a common shaft which is spring urged to provide a peripheral contact between the two sets.

The feeding mechanism may incorporate three sets of rolls, one engaging the strips midway of their widths, and the others engaging close to the respective margins of the strips. The lower rolls of the outer sets of rolls are provided with tread portions terminating at the proper point for freeing the strips from contacting pressure so that feed through these rolls is discontinued at the appropriate point. At this point, the center roll continues the feed until the forms, regardless of their lengths within practical limits,

are substantially delivered; whereupon the tread surface of the center roll or disc engages the upper roll through the enlarged apertures in the paper, and the feed is definitely stopped insofar as the center rolls are concerned. Thereupon, pins associated with the outer rolls move into engagement with the apertures and feed, and align the strips in the final short feeding phase.

The center holes in the paper are of sufficient size to permit lag of the marginal apertures relative to the line of contact of the outer rolls, so that the apertures can be entered by the pins without tearing the paper. The clearance afforded by the large central apertures permits the last feeding phase without any interference from the central rolls. These central rolls continue to engage through the aperture without placing any drag on the strips.

The strips, making up the successive packs of sales forms, include weakened tear-off lines defining the sales forms or slips. Each form includes three apertures which cooperate with the three sets of rolls. The central aperture, as stated, is larger than the marginal apertures, for the purpose of permitting the previously described lag of the marginal apertures and the final aligning feed of the paper without interference from the central set of rolls. These apertures have their centers in transverse alignment. The side apertures may be spaced any desired distance from the side edges; that is, they need not be as near the sides as shown.

The superimposed strips are fed through the rolls in three stages; one, a major feeding operation, in which all three sets of rolls advance the strips; two, an adjusting feeding operation in which the compensating rolls are employed to feed the strips; and three, a minor feeding operation wherein the strips are absolutely aligned and the forms dispensed.

In the first stage, the strips are always advanced a distance slightly less than the shortest form to be used. In this stage, all three of the lower feed rolls engage the strips.

In the second stage, feeding of the strips by means of the two marginal feed rolls is discontinued as engagement by the tread portions ceases. Thereupon, the compensating feed roll alone is effective. The compensating feed roll advances the strips until the central apertures in the superimposed forms are all aligned between the compensating rolls. At this time, the feeding contact of the compensating rolls with the strips is broken since the rolls contact each other through the central apertures. Thus, it

will be obvious that within practical limits, any length of form may be dispensed.

In the third stage or phase of feed, which is referred to as the aligning phase, the pins associated with the outer feed rolls become effective by engagement within the lagging marginal apertures. At this time, of course, the outer feed rolls are out of engagement with the strips and the pins may move in easily and advance the strips by engagement with the forward walls of the marginal apertures. At this time, the strips slip forwardly between the central rolls within the clearance afforded by the large apertures.

Other objects and certain advantages of the present invention will be more fully apparent from a description of the accommodation given

slightly beyond the line of the periphery of the roll. The pins may be made integrally with the feed rolls, as shown, and are positioned on the inside of the roll in each case. The compensating feed roll 35 is mounted on the shaft 24 medially, between the two feed rolls.

The adjusting or compensating feed roll 35 has a continuous tread; that is to say, at no point is it relieved. Thus, it is continuously effective for feeding the paper until it has fed the strips to bring the central apertures in registry between it and its upper roll, as illustrated in Figure 8. The outer feed rolls 34 provide tread portions 40 extending around approximately two-thirds of their circumferences. The balance of the outer

pins without damage to the strips, such as would be the case if the apertures were too far advanced. Therefore, in this final phase of strip advance, the strips are completely aligned; that is to say, the apertures are aligned since the pins contact the forward walls of the apertures and advance the strips by direct contact with the forward edges of the apertures, thus pulling them all into aligned contact against the forward faces of the pins.

Having described my invention, I claim:

1. A pack of sales forms of the type adapted to be fed through a manifolding machine, comprising superimposed strips of paper, including successively arranged sales forms separated by weakened transverse tear lines, said superimposed strips folded in zigzag form on said weakened tear lines, the strips making up the forms including for each form a series of three feed control apertures, said apertures disposed in transverse alignment, the central aperture being of greater size than the outer two, the corresponding apertures of the respective strips and forms being in alignment when the forms are zigzag folded.

2. A continuous strip of sales forms, said forms

adapted to be separated along weakened transverse tear lines, each form including three feed control apertures, one aperture located centrally and being of larger diameter than the others and the other two located in transverse alignment with the first and adjacent the respective sides of the strip.

3. A pack of sales forms of the type adapted to be fed through a manifolding machine, comprising superimposed strips of paper, including successively arranged sales forms separated by weakened tear lines, said superimposed strips folded in zigzag form on said weakened tear lines, the strips making up the forms including for each form a feed control aperture adjacent each respective longitudinal edge of the strips, said last-named apertures being in transverse alignment, and a third aperture disposed medially of the last-named apertures and in transverse alignment therewith, said third aperture being of larger size than the outer two, the apertures of the respective superimposed forms being in alignment when the forms are zigzag folded.
